(57) **CLAIM**

The ornamental design for a candle container, as shown.

DESCRIPTION

FIG. 1 is an elevation view of the candle container.

FIG. 2 is a rear view of the candle container.

FIG. 3 is a side view of the candle container; and,

FIG. 4 is a bottom or top view of the candle container.
The broken line showing is for illustrative purposes only and
forms no part of the claimed design.
